UNITED STATES PATENT OFFICE.

MOSES C. DAVIS AND LUTHER C. KEITH, OF FOLSOM, CALIFORNIA.

IMPROVED WASHING AND PRESSING MACHINE.

Specification forming part of Letters Patent No. 42,567, dated May 3, 1864.

To all whom it may concern:

Be it known that we, M. C. DAVIS and L. C. KEITH, both of Folsom, in the county of Sacramento and State of California, have invented a new and Improved Machine for Pressing and Washing Clothes, &c.; and we do hereby declare that the following is a full, clear, and exact description of the same, reference being had to the accompanying drawings, forming a part of this specification, in which—

Figure 1 represents a side elevation of our invention. Fig. 2 is a plan or top view of the same. Fig. 3 is a transverse vertical section of the same, taken in the plane indicated by the line *xx*, Fig. 2. Fig. 4 is a front elevation, the cover having been removed to expose the working parts. Fig. 5 is a detached view of the ascension and distributing pipe. Similar letters of reference in the several views indicate corresponding parts.

This invention consists in the arrangement of a furnace, hot-water tank, and pump, in combination with a sprinkler and reciprocating pressure-board operated by a hand-lever, connecting with toggle-arms in such a manner that by the action of the hand-lever the pump is set in motion, and a quantity of water from the tank is forced up on the sprinkler and discharged on the clothes hung under said sprinkler, and between it and the pressure-board, and at the same time a gradually-increasing pressure is exerted on the clothes, thus alternately charging them with hot water, and squeezing them dry until all the dirt has been completely removed from the same.

To enable those skilled in the art to make and use our invention, we will proceed to describe it.

A represents a furnace, constructed of sheet-metal or any other suitable material, and provided on its top with a cavity or tank, *B*, capable to receive water. The fire in the furnace strikes the tank on all sides, and the water in the same is heated in a short time, and with a small expenditure of fuel. The furnace is provided with a fire-door, *a*, in front, and a chimney, *b*, in the rear serves to carry off the products of combustion.

C is a pump, which is placed in the interior of the tank, and which is constructed on the anti-friction principle, consisting of a wooden box covered with a flexible diaphragm, to

which a reciprocating motion can be imparted. On raising said diaphragm the air in the pump-box is rarefied, and the water from the tank enters through the valve *C*, and in depressing the diaphragm the water contained in the box is forced out through the valve *d* and up through the pipe *e*, the upper end of which connects with a horizontal pipe or trough, *f*. This trough is perforated with a large number of holes, through which the water is distributed and discharged on the sprinkler *D*. Said sprinkler consists of a flat piece of board or other suitable material, and it is hinged to a bracket, *g*, attached to one of the end plates of the furnace, said end plates being made to extend above the tank, as clearly shown in Fig. 4 of the drawings. On being turned down, the sprinkler rests on a bracket, *g'*, attached to the opposite end plate of the furnace, and on a frame, *E*, which is supported by the brackets *g'g*. Strips *h*, of wood or any suitable material, secured to the ends of the sprinkler, prevent the water running off endwise, and that side of the frame *E* which is opposite the trough *f* also projects above the surface of the sprinkler, so that all the water discharged from the trough is compelled to pass through the perforations in said sprinkler. A button, *i*, connecting with a suitable bolt, serves to lock the sprinkler and to connect it rigidly with the frame *E*.

F is the pressure-board, which is suspended from the frame *E* by means of springs *j*, or by some flexible material, in such a manner that it can readily be moved toward and from the sprinkler, and it is perforated with a large number of holes to allow the water which runs down from the sprinkler to escape into the tank *B* below. A rod, *k*, connects the pressure-board with the diaphragm of the pump, causing the two to move simultaneously.

The motion of the pressure-board and diaphragm is effected by a hand-lever, *l m*, the inner ends of which are bent at right angles, so as to form elbow-levers, and the long arms *l* of said elbow-levers are connected by a cross-bar, which forms the handle. The short arms *m* are connected to pins *n*, which project from the ends of the pressure-board through slots in the end plates of the furnace, and said hand-lever has its fulcrums on pivots *o* in the ends of oscillating levers *p*, which are pivoted to the end plates near their bottom ends. By

these means a toggle arrangement is obtained whereby the pressure-board is forced up toward the sprinkler with gradually-increasing power. The pivots *o*, which work in the slotted end plates of the furnace, are provided with friction rollers *q*, so as to lessen the work of operating the machine.

The clothes or other articles to be washed are suspended from rods *r*, which rest on the rabbeted edges of the side pieces of the frame *E*, and which ought to be placed at such distances apart that the water will be freely distributed over the clothes hung on them, and that the clothes can move up and down freely and without becoming entangled. A movable cover, *H*, which passes over the top of the machine, protects the operator from getting wet.

The operation is as follows: After a fire has been lighted in the furnace to heat a sufficient quantity of water in the tank, the sprinkler is turned back or thrown open and the clothes are hung over the rods *r*, so that their lower edges will touch the pressure-board below when the springs *j* are fully distended. The sprinkler is then replaced and fastened down, and it holds the clothes firmly over the rods, so that the upward pressure will not displace them, and by imparting to the hand-lever an oscillating motion, the pump and the pressure-board are set in motion simultaneously. By the action of the pump a quantity of hot water from the tank *B* is thrown on the sprinkler, and by the action of said sprinkler it is distributed over the clothes. The water thus sucked up by the clothes is squeezed out again by the action of the pressure-board, and at the same time by the expansion and contraction of the springs *j* the position of the clothes is continually

changed, and they are cleaned in the most expeditious manner and without the least injury to the fibers.

It must be remarked that our machine operates in a very different manner from ordinary washing-machines. Instead of the clothes being placed in a body of water and there operated upon by plungers or a pressure-board, we put them in such a position that by the use of a simply-constructed pump, acting alternately with a pressure-board, a column of water is continually forced through and pressed out of the clothes, and the operation of cleaning the clothes is thus effected in the easiest possible manner and in a short time.

What we claim as new, and desire to secure by Letters Patent, is—

1. The tank *B* and furnace *A*, in combination with the pump *C*, sprinkler *D*, and pressure-board *F*, constructed and operating substantially as and for the purpose herein shown and described.
2. The pressure-board *F* and pump *C*, in combination with the hand-lever *l*, constructed and operating in the manner and for the purpose substantially as specified.
3. The hinged sprinkler *D*, in combination with the rabbeted frame *E* and rods *r*, constructed and operating substantially as and for the purposes set forth.
4. The perforated trough *f*, in combination with the pump *C* and sprinkler *D*, constructed and operating as and for the purposes specified.

MOSES C. DAVIS.
LUTHER C. KEITH.
